UNITED STATES PATENT OFFICE.

ALBERT E. SCHAAF AND VOLNEY E. LACY, OF TOLEDO, OHIO.

CARBURETER.

SPECIFICATION forming part of Letters Patent No. 794,951, dated July 18, 1905.

Application filed May 7, 1904. Serial No. 206,863.

To all whom it may concern:

Be it known that we, ALBERT E. SCHAAF and VOLNEY E. LACY, citizens of the United States, residing in the city of Toledo, in the State of Ohio, have invented certain new and useful Improvements in Carbureters, of which the following is a specification, reference being had to the accompanying drawings, forming a part hereof.

10 In the operation of carbureters such as are commonly employed with internal-combustion engines for the formation of the gaseous mixture which constitutes the charge an existing difficulty lies in the inability to maintain the due and proper proportion between the volume of air and the quantity of gasoline under different conditions of operation. Thus in running at slow speed or in starting from a condition of rest with the ordinary carbureter the volume of air supplied for mixture with the gasoline or other vapor is usually in excess of that required for the best results, or when the engine is running at high speed the relative volume of air is less than it should be.

15 It is therefore the object of the present invention to provide a simple and easily-controlled means whereby the volume of air to be mixed with the gasoline or other vapor shall be regulated according to the requirements of the condition under which the engine is operated, so that the quality of the mixture shall be suited always to such varying requirements.

20 The invention will be more fully explained hereinafter with reference to the accompanying drawings, in which, for the purpose of illustration and explanation of the nature of the invention, it is represented as embodied 25 in a convenient and practical form, and in which—

25 Figure 1 is a transverse sectional view of the carbureter which embodies the invention, the plane of section being indicated by the line 1 1 of Fig. 2; and Fig. 2 is a longitudinal sectional view thereof, the plane of section being indicated by the line 2 2 of Fig. 1.

The admission of the gasoline or other liquid employed as the basis of the charge may be regulated by a suitable float-valve, such as 50 that represented in Fig. 1, wherein a chamber *a* receives the gasoline from the source of supply through a needle-valve *b*, the needle *c* of which is suitably weighted, as represented, and is supported by the levers *d*, upon which 55 rests a float *e*. By this device the height of the gasoline in the chamber *a* is maintained without appreciable variation, since any increase immediately raises the float *e*, thereby permitting the valve-needle *c* to descend and 60 close the valve-port, while any decrease causes the valve-needle to rise and open the port wider, the float and the outer arms of the levers slightly overbalancing the weight of the needle and its stem. From the chamber *a* the 65 gasoline flows through a suitable channel to a hollow adjustable plug or nozzle *f*, which is provided at its upper end with a port *f'* for coöperation with a valve-needle *g* and preferably with a recess *f''* in its upper end 70 to retain the gasoline admitted through the port *f'* for vaporization by the current of air which passes over and around the end of the adjustable plug *f*. The last-named needle-valve is preferably located in a sleeve or thimble *h*, placed centrally with respect to the air-inlet *i*, this adjustable plug, needle-valve, and sleeve or thimble forming an aspirator and vaporizer.

75 The shell or casing *k*, which receives and 80 supports the several parts of the carbureter, as herein described, and is provided with the air-inlet *i* and with an outlet *l*, which communicates with the engine, is so formed, preferably by an enlargement or supplemental 85 shell *k'*, as to provide a chamber or passage *k''* for air around the aspirator and vaporizer, such chamber or passage communicating with the outlet *l* beyond the vaporizer through auxiliary air-ports *m'*, preferably triangular or 90 tapered, as clearly shown in Fig. 2, formed in a sleeve or lining *m*, which is fixed in the shell *k*. The sleeve *m* terminates within an enlargement *k''* of the shell or casing *k*, so that

a free passage for the air and vapor is provided around the end of the sleeve m , all of which must pass through said sleeve m . A guide sleeve or lining n may also be supported by the casing k opposite and in line with the sleeve m , but separated therefrom, as clearly shown in Fig. 2. Arranged to move in the sleeves m and n is a throttle-plunger, comprising a cylindrical portion o within the sleeve m , a second cylindrical portion o' , connected with the portion o by arms or bridges o^2 , and a stem o^3 , by which the position of the throttle-plunger may be controlled. The end of the portion o' nearest to the portion o of the throttle-plunger is preferably provided with V -shaped notches o^4 for a purpose presently to be described. It will be observed that the thimble h of the aspirator and vaporizer is preferably extended within the sleeve portion o of the throttle-plunger, so that whatever air is drawn through the auxiliary air-ports m' may assist the action of the aspirator and vaporizer and be thoroughly mixed with the vapor which is delivered by the sleeve or thimble h .

In the operation of the device it will be understood that when the throttle-plunger is moved to the left in Fig. 2 to its limit the auxiliary air-ports m' will be closed by the sleeve portion o , and the V -shaped notches o^4 in the sleeve portion o' will be covered by the sleeve m , so that no air and no mixture of air and vapor passes to the outlet l . As the throttle-plunger is moved to the right, however, the notches o^4 are opened rapidly and the auxiliary air-ports m' are opened slowly, so that in starting up the engine from a condition of rest not only is the delivery of mixture to the engine restricted, but substantially all of the air which enters into the mixture is that which passes through the aspirator and vaporizer, the volume of air thus being proportioned to the quantity of gasoline delivered by the needle-valve f' g , while as the movement of the throttle-plunger to the right is continued the end of the sleeve portion o' clears the end of the sleeve m , permitting a freer delivery of mixture to the outlet, and the auxiliary air-ports m' are opened farther, permitting an additional volume of air to be drawn in to be mingled with the richer mixture of air and vapor delivered through the thimble h . In this manner the quantity of auxiliary air is increased until the throttle is opened to its widest extent, keeping pace with the increasing quantity of gasoline supplied and vaporized by the aspirator and vaporizer, thus securing under all conditions of operation that quality of the mixture which is most satisfactory. It will be understood that the quantity of gasoline supplied may be regulated at all times by the needle-valve g . It will be also understood that the form and arrangement of the

several parts of the improved carburetor may be varied to meet different conditions of use as may be required without departing from the spirit of the invention.

We claim as our invention—

1. A carburetor, comprising a casing having an inlet and an outlet, a thimble located within said casing and having an air-passage therethrough, means to supply the fluid basis of the charge to said thimble, a sleeve extended from said thimble to said outlet and having auxiliary air-ports therein, and a sleeve-like throttle-plunger arranged to slide within the first-named sleeve and to control said auxiliary air-ports and vary the quantity of air admitted therethrough, substantially as described. 75

2. A carburetor, comprising a casing having an inlet and an outlet, a thimble located within said casing and having an air-passage therethrough, means to supply the fluid basis of the charge to said thimble, a sleeve extended from said thimble to said outlet and having auxiliary air-ports therein, a sleeve-like throttle-plunger arranged to slide in the first-named sleeve and to control said auxiliary air-ports and vary the quantity of air admitted therethrough and communicating with the outlet and a second sleeve-like throttle-plunger connected with the first throttle-plunger and arranged to slide in the first-named sleeve to control the outlet, substantially as described. 90

3. A carburetor, comprising a casing having an inlet and an outlet, a thimble located in said casing and having an air-passage therethrough, means to supply the fluid basis of the charge to said thimble, a sleeve extended from said thimble to said outlet and having triangular air-ports therein, a sleeve-like plunger arranged to slide in the first-named sleeve and to control said triangular air-ports to vary the quantity of air admitted therethrough, a second sleeve-like throttle-plunger arranged to coöperate with the end of the first-named sleeve to control the outlet, and arms connecting the second throttle-plunger to the first throttle-plunger, substantially as described. 100

4. A carburetor comprising a casing having an inlet and an outlet, a thimble located within said casing and having an air-passage therethrough, means to supply the fluid basis of the charge to said thimble, a sleeve in alignment with said thimble and having auxiliary air-ports therein, and a sleeve-like throttle-plunger arranged to slide within the first-named sleeve and to control said auxiliary air-ports and vary the quantity of air admitted therethrough, substantially as described. 115

5. A carburetor comprising a casing having an inlet and an outlet, a thimble located within said casing and having an air-passage therethrough, means to supply the fluid basis 120

125

of the charge to said thimble, a sleeve in alignment with said thimble and having auxiliary air-ports therein, a sleeve-like throttle-plunger arranged to slide in the first-named sleeve and to control said auxiliary air-ports and vary the quantity of air admitted therethrough and also to control the outlet, substantially as described.

This specification signed and witnessed this 2d day of May, A. D. 1904.
